UNITED STATES PATENT OFFICE.

WILLIAM H. FANNING, OF LAPEER, MICHIGAN.

ROAD-CART.

SPECIFICATION forming part of Letters Patent No. 445,427, dated January 27, 1891.

Application filed June 2, 1890. Serial No. 353,910. (No model.)

To all whom it may concern:

Be it known that I, WILLIAM H. FANNING, a citizen of the United States, residing at Lapeer, county of Lapeer, State of Michigan, 5 have invented a certain new and useful Improvement in Road-Carts; and I declare the following to be a full, clear, and exact description of the invention, such as will enable others skilled in the art to which it pertains to 10 make and use the same, reference being had to the accompanying drawings, which form a part of this specification.

My invention is designed to produce a road-cart in which the body is so supported by 15 springs, both at the front and rear, that it shall be rendered exceedingly easy for the occupant; and it consists in a combination of devices and appliances hereinafter described and claimed.

20 In the drawings, Figure 1 is a side elevation of my cart. Fig. 2 is a plan view. Fig. 3 illustrates a detail of construction.

In carrying out the invention, A represents 25 the body, B the axle having the spindle b broken off, and C the shafts.

C' is the cross-bar extending from one shaft to the other in front of the body.

D is a leaf-spring, one end d being engaged 30 to the cross-bar. The spring is then curved into a somewhat C form, as shown—that is, it is curved upward, forward, then downward and rearward, the end d' being engaged to the forward edge of the body. It will be, of course, understood that there is one of these 35 springs D on each side, as shown in Fig. 2.

I will now describe the manner of supporting the rear portion of the body.

The axle, as will be observed in Fig. 3, is bowed or bent downward slightly between the 40 wheels, and projecting inward from the point on the axle adjacent to the spindle is the arm or projection B'.

E are suitably-bent pieces, the lower end e being rigidly engaged to the arm B', while 45 the upper end e' is engaged to a cross-piece F, connecting the two bent pieces together.

G are what may be termed "standards" or "braces," and extend at an oblique angle from the rear portion of the shafts up to the cross-bar F. Each of these standards has what may 50 be termed a "removable base-section" g, so shaped that one portion may be engaged with the shaft by the bolts g', while the other portion is engaged to the standard by the bolts

g². The upper end of the standard is engaged 55 to the cross-bar by a similar piece g³.

In order that an additional truss may be given to this frame-work at the rear of the cart, I provide the brace-iron H, extending from the rear portion of the shaft up to the 60 cross-bar.

J is a leaf-spring in the form of a C-spring, one end j being engaged by a clevis, with an arm K extending out rearwardly from the body. 65

L is what may be termed an "angle-iron," one arm shaped to conform to the curvature of the bent piece E, while the other arm is engaged to the end j' of the spring J by the bolt j². It will be seen that by this construction the body is supported in such a way that it may have a free forward-and-back or up-and down motion—that is to say, the peculiar arrangement of the springs allows it to yield with the weight and move up and down, while 75 the same arrangement allows it to sway forward and back freely.

What I claim is—

1. The combination, with the axle B, the shafts C, and the body A, having its forward 80 portion suspended from the shafts by the curved leaf-spring D, of a frame rising from the shafts and axle in rear of the body, and the C-springs connected to the upper end of the frame and the rear end of the body, substantially as described.

2. In a road-cart, the combination, with the shafts, the body, and C-springs pivotally engaged to the rear portion of the body, of a frame-work for supporting said C-springs, 90 consisting of the curved pieces E, standards G, and cross-bars F, substantially as described.

3. In a road-cart, the combination, with the shafts, the body, and C-springs pivotally engaged to the rear portion of the body, of a frame-work for supporting said C-springs, 95 said frame-work consisting of the curved pieces E, cross-bar F, and standards G, said standards consisting of the main portion G 100 and end pieces g g², substantially as described.

In testimony whereof I sign this specification in the presence of two witnesses.

WILLIAM H. FANNING.
